UNITED STATES PATENT OFFICE.

CHARLES HAINES, OF CANTON, OHIO, ASSIGNOR TO THE BERGER MANUFACTURING COMPANY, OF CANTON, OHIO, A CORPORATION.

FENCE-POST.

1,283,163.

Specification of Letters Patent. Patented Oct. 29, 1918.

Application filed June 10, 1916. Serial No. 102,815.

To all whom it may concern:

Be it known that I, CHARLES HAINES, a citizen of the United States, residing at Canton, in the county of Stark and State of 5 Ohio, have invented certain new and useful Improvements in Fence-Posts, of which the following is a specification.

The invention relates to metal posts for fences and the like, and the object of the 10 improvement is to provide simple means for securing a plurality of wire strands to one face or edge of the post.

The desired object of the invention is accomplished by forming or shaping a hollow 15 cavity within the attaching face or edge of the post, and by providing apertures in the wall of the post for receiving the prongs of an ordinary staple, and providing converging faces in the sides of the hollow or cavity 20 for deflecting the prongs of the staple toward and across each other when the same are driven into or through the apertures.

The invention, in several modified forms 25 of post, is illustrated in the accompanying drawings, forming part hereof, in which—

Figure 1 is a face elevation of a metal post showing horizontal strands of wire secured thereto;

Fig. 2, a fragmentary section on line 2—2 30 of Fig. 1, showing one strand of wire secured to the post by a staple;

Fig. 3, a fragmentary face view of the same form of post showing a wire strand secured thereto by a staple;

Fig. 4, a fragmentary rear view of the same;

Fig. 5, a section as on line 5—5, Fig. 2;

Fig. 6, a similar section showing a modified shape of post;

Fig. 7, a fragmentary side elevation showing a modified form of post; and

Fig. 8, a fragmentary section on line 8—8, Fig. 7.

Similar numerals refer to similar parts 45 throughout the drawings.

The post 1 is preferably made of malleable or rolled metal of a general V-shape in cross-section, as shown in Fig. 5, the edges of which may be formed with the retracted 50 flanges 2 for giving additional strength to the post. In each side of the post and at an interval from the adjacent V-angle 3 thereof, is provided the longitudinal bead or corrugation 4, which is deflected inwardly from the side face of the post, the

inner sides of which corrugations form the converging faces 5 on each side of the hollow thus formed in the V-angle of the post.

The laterally spaced apertures 7 are provided, one on each side of the V-angle 3 in 60 the side walls of the post between the V-angle 3 and the corrugations 4 thereof, one of which apertures is preferably located above the height of the other, so that when the prongs of the staple are driven into the 65 apertures, the yoke 9 thereof will diagonally straddle either the horizontal wire 10 or a vertical wire, not shown, for securing the same to the post; such wire being clamped by the staple against the vertical longitudinal rib formed by the V-angle of the 70 post between the diagonally spaced apertures therein.

By this construction and arrangement it is evident that by inserting and driving the 75 staple through the apertures in the post, the prongs 8 of the staple will impinge the converging faces 5 in the side walls thereof, and will thereby be deflected inward and across each other in the manner clearly illustrated 80 in Fig. 5 of the drawings; and that when the wire 10 has been thus secured to the post, the staple cannot be withdrawn therefrom without such a drawing or pulling force as will again straighten the prongs of the staple. 85

By these means a strand of wire either horizontal or vertical, as may be desired, may be secured to the metal post by the mere use of an ordinary staple driven into the post, as described, without employing any 90 special tools or appliances for that purpose.

Fig. 6 shows a slightly modified shape of post wherein the V-angle 3^a thereof is rounded to form a wider face for abutting the wire 10. Otherwise the corrugations 4^a 95 and the converging faces 5^a in the cavity of the post are formed substantially the same as in the shape thereof illustrated in Figs. 1 to 5, inclusive.

Figs. 7 and 8 show a modified form of post 100 in which indentations 4^b are provided in the side walls thereof in place of the longitudinal corrugations 4 extending throughout the length of the post. It is evident, however, that the converging walls 5^b formed 105 by these indentations will serve to deflect the prongs 8 toward and across each other in the same manner that these prongs are deflected by the corresponding faces of the corrugations. 110

I claim:

1. A fence post having a longitudinal cavity within its wall, spaced apertures in the wall, and converging faces in the sides 5 of the cavity for deflecting across the cavity and toward each other the prongs of a staple driven into the apertures.
2. A fence post formed with a V-shaped wall, an aperture on each side of the V-angle 10 of the wall, and converging faces formed on the inner side of the wall for deflecting

toward each other the prongs of a staple driven into the apertures.

3. A fence post formed with a V-shaped wall, an aperture on each side of the V- 15 angle of the wall, and longitudinal corrugations adjacent to the V-angle of the post forming converging faces for deflecting toward each other the prongs of a staple driven into the apertures.

CHARLES HAINES.
